UNITED STATES PATENT OFFICE.

SYDNEY B. WERTHEIMER, OF BROOKLYN, NEW YORK.

LUSTROUS FABRIC FOR DECORATIVE PURPOSES.

Application filed October 16, 1924. Serial No. 744,064.

To all whom it may concern:

Be it known that I, SYDNEY B. WERTHEIMER, a citizen of the United States, and a resident of the city of New York, borough 5 of Brooklyn, in the county of Kings and State of New York, have invented a new and Improved Lustrous Fabric for Decorative Purposes, of which the following is a full, clear, and exact description.

10 This invention relates to a lustrous fabric for decorative purposes.

An object of the invention is to provide a lustrous fabric for decorative purposes which is strong and durable so that it can 15 be handled considerably without tearing or ripping or without losing its shape and, at the same time, retain its high luster.

The invention is illustrated in the drawings, of which—

20 Figure 1 is a plan view of a portion of the fabric; and

Figure 2 is a section taken on the line 2—2 of Figure 1.

The form of the invention shown in the 25 drawings is a preferred form, although it is understood that modifications in the construction and arrangement of the parts and in the character of the materials used may be adopted without departing from the 30 spirit of the invention as set forth in the appended claims.

In accordance with my invention, I propose to take a plurality of flat threads of lustrous material, known as "visca artificial 35 silk", and use them as warp threads of a fabric to be formed. These warp threads may be of any suitable size, shape or material. For example, they may be a plurality of rectangular section threads of 40 artificial silk laid closely together side by side. The idea in this particular case would be to bind them together in such a manner that they would be formed into a fabric of considerable durability and strength and yet 45 so woven with the woof thread that the woof thread would not detract from or impair the luster of the warp thread. For example, I propose to weave into a plurality of warp threads of high luster a single fine

50 thread of material, rather loosely woven so that it acts as a sufficient binder to form a firm, durable fabric but by reason of the looseness of the weave of the woof thread the luster of the warp thread is not substantially affected.

For example, if I have a plurality of flat

warp threads of visca artificial silk, I may weave into them a single fine thread of real silk which can be woven back and forth loosely and at spaced intervals of sufficient 60 distance so that the woof thread does not detract from the luster and yet will produce a fabric of the proper strength and durability.

I also aim to provide such a fabric along 65 its edges with warp threads of different material, preferably a round cotton thread of greater normal strength than the regular flat visca artificial silk warp threads, over which the woof thread can be looped or 70 woven to produce an additional reinforcement along the edges of the fabric. If the round cotton edge threads were omitted, the sharp edges of the flat visca thread would 75 cut the thin single woof thread of silk, thereby retarding the weaving.

As shown in the drawings, the preferred 80 form of the invention, which is used merely to illustrate the idea, comprises a plurality of warp threads such as 1, which are preferably flat in cross section and may be of artificial silk of high luster. Disposed along the longitudinal edges of the fabric are reinforcing threads 2 and 3, which are preferably 85 single threads of cotton which has a greater strength than artificial silk. Woven across the warp threads is a woof thread 4, which is preferably a single, fine thread of real silk. This woof thread is woven loosely 90 across the warp threads and the spacing is of considerable dimension between successive portions of the woof thread, so that although the woof thread holds the warp thread firmly together to form a firm, durable fabric, it is not closely enough woven 95 to in any appreciable way affect the luster of the flat visca artificial silk warp threads.

In this manner, therefore, I obtain a ribbonlike material of high luster having its edges reinforced and held together by a woof 100 thread to a sufficient degree to form a firm, durable fabric but which, nevertheless, retains substantially all of its luster so that it is highly useful and ornamental for decorative purposes.

What I claim is:—

1. A lustrous fabric, which comprises a plurality of flat warp threads of lustrous material, and a woof thread loosely woven therewith so as to bind the warp threads 110 together without materially affecting their luster,

2. A lustrous fabric for decorative purposes, which comprises a plurality of highly lustrous flat warp threads bound together by a single fine woof thread woven loosely therewith. 20
3. A lustrous fabric for decorative purposes, which comprises a plurality of flat warp threads of high luster, a round warp thread of different material and greater strength than the normal warp threads disposed along each edge of the fabric, and a single fine woof thread woven loosely across the fabric and looped over the warp threads at the edges of the fabric, said woof thread 25
- 10 in its successive portions across the fabric being spaced a considerable distance apart to bind the fabric firmly together without affecting the luster of the normal warp threads. 30
- 15
4. A lustrous fabric to be used for decorative purposes, which comprises a plurality of flat warp threads of artificial silk, a cotton warp thread of greater strength than the silk warp thread disposed along each edge of the fabric, and a single thin woof thread 35 of real silk woven loosely across the fabric. 35
5. A lustrous fabric to be used for decorative purposes, which comprises a plurality of flat warp threads of artificial silk, a cotton warp thread of greater strength than the silk warp thread disposed along each edge of the fabric, and a single thin woof thread of real silk woven loosely across the fabric, several woof threads being looped over the cotton threads at each edge of the fabric. 40

SYDNEY B. WERTHEIMER.
